FURNITURE CONSTRUCTION

Nathan M. Weiss, Compton, Calif., assignor to
Cali-Quilt Furniture Mfg. Co., Lynwood, Calif.

Application September 19, 1949, Serial No. 116,501

3 Claims. (Cl. 155—184)

1

My present invention has to do with furniture construction and has as an object the provision of an improved article of furniture such as a settee or divan.

A further object is the provision of an improved type of furniture construction which is particularly well suited for making divans of the type which is convertible into a full sized bed when desired.

A long existing shortcoming of conventional settee or divan construction is that the padding is mounted on the spring element in such a manner that too much reliance and stress are placed upon the upholstering or cover sheet. Another shortcoming is that in conventional construction the different layers going to make up the padding element tend to shift relative to each other and relative to the spring.

It is an object of my invention to overcome those shortcomings.

It is a further object to provide a novel type of divan capable of being readily converted into a comfortable full sized bed and wherein I am able to employ a single unitary pad element for both the relatively movable seat and back rest portions.

A still further object is to provide a settee or divan construction wherein the upholstering or cover sheet, the padding layer and the inner layer are formed into a unitary assembly stitched together by a continuous lock-stitch.

Other objects will appear hereinafter.

Without intending thereby to limit the broader scope of my invention as defined by the appended claims, I shall now describe the invention in one of its presently preferred embodiments, for which purpose I shall refer to the drawings, wherein:

Fig. 1 is a front elevation of a divan or settee made in accordance with my invention;

Fig. 2 is a section taken on line 2—2 of Fig. 1, but showing the divan converted into a bed;

Fig. 3 is an enlarged perspective view illustrating the several layers or sheets constituting the pad element; said sheets being arranged inversely to the order in which they appear in the finished product;

Fig. 4 is a perspective of the pad in inverted position;

Fig. 5 is an enlarged cross-section taken on line 5—5 of Fig. 4, but showing the pad element in position to be mounted on the spring assembly;

Fig. 6 is an enlarged fragmentary section taken on line 6—6 of Fig. 1;

Fig. 7 is an enlarged fragmentary section taken on line 7—7 of Fig. 2;

2

Fig. 8 is a perspective view of a day bed or studio couch embodying a modified form of my invention;

Fig. 9 is an enlarged perspective view illustrating the several layers or sheets constituting the pad element of the structure shown in Fig. 8; and

Fig. 10 is an enlarged sectional view of the pad element used on connection with the structure shown in Fig. 8.

Referring now to the drawings, I show at 5 a settee or divan of the type which is convertible into a full sized bed, as shown in Fig. 2, and comprising a base 7, seat element 8, back rest 9 and side members 10.

The seat and back rest elements each have a wooden base frame 15, see Fig. 6, to which the spring element 16 is fastened as by staples 17, or in any other suitable manner. The spring element may be conventional in form and comprises a wire frame 16a carrying coils 16b.

In Fig. 3 I show the sheets or layers of material comprising the pad element used in my construction, those being, an outer layer 18 of upholstering fabric forming the cover sheet, an intermediate layer 19 of cotton batting or other suitable padding material, and a bottom sheet 20 of muslin, burlap or other suitable material.

I superimpose these sheets, one on the other, in the order named, and secure them together, preferably by a continuous quilting lock stitch 21, to form a single, unitary pad element 22 of a size to serve both as the pad element for the seat and as the pad element for the back rest.

As best shown in Figs. 4, 5, and 6, I secure to the pad element 22, a pair of superimposed flexible stretcher strips of fabric or the like, denoted 23 and 24 in the drawing. These stretcher strips are secured to the pad element in the following manner: first, their contiguous side edges 23a and 24a are placed against the bottom surface of the pad element medially and transversely thereof; and then I make a lock stitch 25 extending transversely of the pad element, which stitching not only secures the edge portions of the stretcher strips to the pad element, but also extends through the pad element to draw the inner layer 20 and the outer layer 18 toward each other, compressing the padding layer 19 therebetween to provide a hinge area 22c at the intersection of that portion 22a of the pad element which covers the seat portion 8 of the divan and that portion 22b which covers the back rest portion 9.

As best shown in Figs. 5 and 6, the marginal

portions 18a and 20a, respectively, of the cover sheet 18 and the inner sheet 20, extend outwardly beyond the outer edges 19a of the padding sheet 19; and their extreme marginal portions 18b and 20b are folded under the bottom of the wooden frames 15 and secured thereto as by tacks 26 and 27, see Fig. 7. To permit the marginal portions of sheets 18, 20 to be thus mounted about the inner corners of the seat and back rest frames, I provide a slit 31 in each of said sheets, extending outwardly from the ends of the stretcher strips. Thus, the marginal portions of both the inner and outer sheets or layers are securely anchored, in stretched condition, to the wood frame, while the padding layer is between and 15 stitched to said layers. In my said construction, it is impossible for the sheets or layers to shift relative to each other or relative to the spring element; and the stresses which the outer sheet must bear alone in conventional construction, 20 are shared by the inner sheet.

It will be apparent from the foregoing description that a single unitary pad element covers both the seat portion and the back rest portion of the divan, the pad element being suitably 25 hinged transversely along its middle to facilitate swinging the back rest upright when the device is being used as a divan, and, to swing it into horizontal position alongside the seat portion, when it is desired to convert the device into a bed. The stretcher strips securely anchor the pad element to the wood frames against the pressure of the spring element, drawing not only 30 the cover sheet but also the bottom sheet and padding toward the wood frames along a transverse line intermediate the seat and back rest portions. By securing one of the stretcher strips 24, by means of tacks 27, to the seat frame and the other stretcher strip 23, by means of tacks 28, to the back rest frame, the relative swinging movement of those frames does not impose 35 any stress upon the pad element. The stitching of the stretcher strips to the pad element is done in such manner that no direct pull on the stitching is exerted.

In Figs. 8, 9 and 10, I show a modified form embodying the general principle of the structure previously described, but with a slight variation. Here, the seat portion 8' of a conventional day bed, comprises a spring unit 16 and a wood frame 15 in substantially the same unitary structure as in the first preferred embodiment, except, however, that in this arrangement the unitary pad 22' differs in that it is made to cover only the seat portion and hence the previously mentioned stretcher strips are eliminated. The pad comprises the sheets or layers 18', 19' and 20', all similar to those in the previously described form. The quilting stitching 21' is also applied in the manner previously described and the application of the unitary pad to the spring frame is the same except that in this case all four edges are applied as shown in Fig. 7.

I claim:

1. In an article of furniture, a pair of rectangular frames disposed in side edge to side edge juxtaposition for relative swinging movement, coil springs mounted uprightly on said frames, a single upholstering pad element overlying both said frames and resiliently supported upon said springs, said pad element being stretched tautly over said springs and having its side and end marginal portions secured to said frames, and tension means between the contiguous edges of said frames drawing said pad element toward said frames against the pressure of said springs along a transverse line medially between the ends of said pad element, said tension means comprising a pair of flexible strips secured along one of their side edge portions to said pad element along said transverse line, one of said strips being secured along its opposite side edge portion to one of said frames and the other of said strips being secured along its opposite side edge portion to the other of said frames.

2. In an article of furniture, a pair of frames disposed in side edge to side edge juxtaposition for relative swinging movement, springs carried by each frame, a pad element overlying and resiliently supported on said springs, said pad element comprising top and bottom flexible sheets and a padding material therebetween, the marginal portions of said sheets extending beyond said padding material and being secured to said frames, and tension means comprising a pair of flexible strips secured along one of their side edge portions to said pad element along a transverse medial line; one of said strips being secured along its opposite side edge portion to one of said frames and the other of said strips being secured along its opposite side edge portion to one other of said frames; said strips being of a width to maintain said pad element taut along its medial transverse portion.

3. The article of claim 2 wherein said sheets and padding material comprising said pad element are secured together by quilting stitching and wherein said quilting stitching secures one side edge portion of said strips to said pad element.

NATHAN M. WEISS.
